Inventor

Leo Oppenheim,
By his Attorney, *Geo. H. Syms*

UNITED STATES PATENT OFFICE.

LEO OPPENHEIM, OF NEW YORK, N. Y.

CALENDAR.

1,415,686.

Specification of Letters Patent.

Patented May 9, 1922.

Application filed February 2, 1922. Serial No. 533,587.

To all whom it may concern:

Be it known that I, LEO OPPENHEIM, a citizen of the United States, residing at New York, county and State of New York, have 5 invented a new and useful Improvement in Calendars, of which the following is a specification.

This invention relates to improvements in 10 calendars and is more particularly designed as an improvement upon calendars of the character shown and described in U. S. Re-issue Patent No. 13,593.

The main object of the invention is to 15 provide means to readily distinguish the present day and date from the past and future days and date of a month. To this end the invention consists in combining an indicating device with a casing adapted for holding and displaying a month sheet and 20 so arranging the several parts as to admit of the indicating device operating over the face of the month sheet.

Other objects will appear from the following description, reference being had to 25 the accompanying drawings in which—

Figure 1 is a front elevational view of the invention.

Figure 2 is a horizontal cross sectional view and

30 Figure 3 is a contracted plan view of the indicating device.

Heretofore in calendars of this sort a flexible strip or web was provided with a series of lines arranged in echelon in order 35 that expired dates on a date sheet arranged behind may be cancelled and by means of these lines, the present date is indicated. This arrangement has not proven entirely satisfactory because the series of cancellation lines passing over the expired dates 40 act to partially obliterate the dates, thereby making them obscure and rather hard to see when one wishes to refer to a passed or cancelled date. The present inventor who 45 is also the owner and manufacturer of the above mentioned calendar has by means of the present invention overcome this objectionable feature by doing away with the cancellation lines entirely and providing the 50 flexible web with a series of circles forming bull's eyes within which appears the present date of the month which may be readily distinguished at a glance. Through this means it is obvious that the passed dates are always 55 visible for ready reference when occasion requires.

The casing *a* may be formed of any suitable sheet material such as wood, and the base block 5 may be of the same or different material. Said base block may be integral 60 with or otherwise connected to the casing and by preference is formed with an oblique upper face 6 or otherwise constructed so as to give a pitch or tilt to the casing, to maintain the latter more directly in the line 65 of vision when resting upon a desk, or the like.

The base and casing may be covered with any suitable material such as leather, or otherwise decorated so as to lend to the attractiveness of the device.

The casing *a* is interiorly provided with a pocket 7 which is open at its ends and top and the inner side of which is formed by a plate 8 arranged so as to form a support for the month sheets 9, the latter being of any approved construction and if desired provided with printed matter in addition to what is required for indicating the days, dates and name of any month. A number 80 of cards corresponding to the number of months in one or more years may be employed or successive months may be printed on the opposite faces. The pocket 7 and the opening in the upper end thereof are 85 of such size as to readily admit of the introduction thereto of the month sheets, and the upper side portions of the latter project through the open upper end 10 of the pocket to present convenient finger holds when 90 changing or arranging the sheets.

The front side 11 of the pocket has an opening 12 whose area is such that all the necessary printed matter on the surface of the sheet may be seen.

95 Interposed between the month sheets and the outer side 11 of the casing is a highly transparent indicating web 13 formed of suitable material, such as very thin celluloid. The width of this web is at least equal 100 to the combined width of the longitudinal rows of figures on any month sheet and preferably will be greater than that of the opening 12. The end portions of the web are connected to drums 15 and 16, arranged in 105 compartments 17—17 which communicate with the pocket 7, the lower ends of the drums being provided with trunnions 18, supported in bearings in the bottom of the said compartments. The upper ends of the 110 drums are also provided with trunnions 19 which pass through bushings 20 in the top

10 of the casing and are surmounted with milled nuts 21 forming convenient turning means for the drums.

Associated with the trunnions 19 of the 5 drums are friction devices in the form of coil springs 22 which are arranged so as to contact with the inner surface of the casing, to prevent accidental movement of the drums under a tendency of the indicating 10 web to coil or bend between the drums after the setting or adjusting of the web.

To additionally prevent any buckling or bending of the indicating web and to protect the same from damage resulting from 15 direct handling, or blows or the like, a panel 26 of glass or other transparent material is interposed between the web and front wall 11 of the casing.

As shown in Figure 3 the transparent indicating web is provided with a series of circles 23 forming bull's-eyes arranged in echelon or step form so that when the web is moved from left to right (Figure 1) across the numerals on the visible month 20 sheet, the numerals will appear within the bull's eye successively, and stand out promptly when encircled thereby. The horizontal interval between any two bull's-eyes is equal to the horizontal length of the 25 date sheet.

In use, the surface having imprinted thereon the desired month, is arranged so as to be visible through the opening 12 and through the transparent web 13. Now, we 30 assume that this arrangement is made on the first day of the month, then the web will have been turned until the first bull's-eye encircles the numeral 1. Now, upon the passing of the first day the operator turns 35

the knob on the right in Figure 1 and the 40 bull's eye passes from the numeral 1 and encircles the numeral 2, thus indicating that it is the second day of the month. This action is repeated on the second and subsequent days so as to indicate the days successively, it being obvious that the past days are visible cancelled. Upon the passing of the last day of the month, the month sheet is turned or replaced as the case may be, so as to have the surface provided with matter for indicating the succeeding month, visible through the opening 12 and at such time of arranging the cards the web is operated to re-set the indicating device as previously described. 55

Having now particularly described and ascertained the nature of my said invention and in what manner the same is to be performed, I declare that what I claim is:—

In a calendar, the combination of a casing having an opening in the front side thereof, a month sheet removably mounted within the casing and visible through the opening and a movable indicating web mounted within the casing and arranged 60 over the visible surface of the month sheet, said web provided with a series of circles arranged in echelon in order that dates on the month sheet may be successively indicated when the web is moved. 65

In testimony whereof, I have signed my name to this specification in the presence of two subscribing witnesses, this 17th day of January, 1922.

LEO OPPENHEIM.
